UNITED STATES PATENT OFFICE

GEORGE A. BREWSTER, OF BUFFALO, NEW YORK

OPERATING TABLE

Application filed April 16, 1929. Serial No. 355,510.

This invention relates to improvements in operating tables and proposes a table which is particularly suitable for use in connection with osteopathic treatments. It may be pointed out that in the practice of osteopathy, it is desirable to support the patient, face downward, upon a table and to adjust portions of the supporting surface provided by the table in order to bring the parts of the body of the patient to a certain position or alignment at which complete relaxation is either promoted or facilitated.

The principal object of the invention is to provide a table upon which a patient may lie, which may be adjusted so that the weight of the patient will cause the top portions of the table to move automatically to a position at which the parts of the body of the patient is placed in proper alignment.

Another object of the invention is to provide a table which may readily be adjusted to accommodate the weight of a patient and which, when adjusted, will support the patient resiliently in the desired position.

A further object is to provide a simple, sturdy and compact construction which may be inexpensively manufactured.

The invention primarily resides in pivotally mounting conterminous supporting sections of the table, the adjacent ends of which are adapted to move downward by virtue of the weight of the patient, and providing resilient means to regulate or control the downward movement so as to bring the parts of the body of the patient to, and resiliently maintain them in, the desired alignment.

An embodiment of the invention is illustrated in the accompanying drawing, wherefore:

Figure 1 is a side elevation of the table.
Figure 2 is a top plan view of the same.

Figure 3 is an end elevation.

Figure 4 is an enlarged fragmentary section along line 4-4 of Fig. 3.

In accordance with the invention, a patient supporting surface is provided by a pair of conterminous top sections 1, each of which is pivotally mounted on separate cross or pivot rods 2. The pivot rods 2 may be supported in any suitable manner, the support here-

in shown consisting of oppositely disposed triangular side frames 3 for each top section 1, each side frame being provided with supporting legs 4. The support for the sections also includes cross bars 5 which extend between, and are secured to, the oppositely disposed side frames 3 at each side thereof, these bars serving to maintain the spacing of the side frames 3 and to increase the rigidity of the construction. The proper space relation between the centrally located or inner ends of the top sections 1 is maintained by connecting the side frames of each section through separate rods 6 to a common tie rod 7. It may be pointed out that each pivot rod 2 is spaced away from the center of its respective section so as to extend more closely to the outer end thereof than the inner end whereby the inner or adjacent ends of the sections are adapted to move downward by virtue of the weight of a patient who is arranged upon the supporting surface provided by the sections.

The invention, as stated, also includes a resilient means for regulating or controlling the downward movement of adjacent ends of the top sections 1. The resilient means, herein provided, include a semi-circular rod 8 carried by each top section 1, each rod being arranged concentrically about the pivot rod 2 on which its particular section is mounted and preferably arranged to pass through a suitable recess formed in each cross bar 5. Each rod 8 carries a pair of springs 9 and 10, one spring on either side of the cross bar 5 extending nearest the center of the table; in other words the "inner" cross bar. The spring 9 extends from a collar 11 which abuts the inner cross bar 5, to the under surface of that particular section while the spring 10 extends between the collars 12 and 13 which abut the inner and outer cross bars 5 respectively. The collars 12 and 13 normally are loose on the rod 8 but they may, when desired, be fixed thereto by the set screws shown. To hold the sections against retrograde tipping movement, each rod 8 carries an additional collar 14 which is fixed to the rod at a point such as to abut the outer

cross bar 5 when the top section occupies its normal or horizontal position.

It is evident that the weight of a patient lying upon the table, will cause the adjacent 5 ends of the sections 1 to move downward. This downward movement may, in the case of patients of average weight, be resisted or regulated solely by the springs 9. If the patient be a person of greater than average 10 weight, both springs 9 and 10 are utilized, the collars 12 in such case being fixed to the rods 8. By the use of suitable springs, the arrangement, in either case, is effective to bring the parts of the body of the patient 15 automatically to the desired alignment. When it is desired to hold the sections in a horizontal position or at some particular inclination, it is only necessary to arrange the sections in such position and then secure the 20 collars 13 to the rods 8, these collars cooperating with the outer cross bars 5 to prevent further movement of the rods 8.

Having described my invention, I claim:

1. An operating table of the class described 25 comprising supporting means, sections arranged end to end and pivotally mounted on said means intermediate their ends to provide a supporting surface upon which a patient may lie, the adjacent ends of the sections being adapted to move downward by virtue of the weight of the patient, and spring means for automatically controlling the downward movement of said adjacent ends so as to align the parts of the body of the 30 patient and resiliently maintain them in such alignment.

2. An operating table of the class described comprising supporting means, sections arranged end to end and pivotally mounted 40 on said means intermediate their ends to provide a supporting surface upon which a patient may lie, the adjacent ends of the sections being adapted to move downward by virtue of the weight of the patient, resilient 45 means for automatically controlling the downward movement of said adjacent ends so as to align the parts of the body of the patient and resiliently maintain them in such alignment and stops for preventing a retrograde movement of the sections substantially 50 beyond their normal end to end position.

3. An operating table of the class described comprising supporting means, sections arranged end to end and pivotally mounted on 55 said means intermediate their ends to provide a supporting surface upon which a patient may lie, the adjacent ends of the sections being adapted to move downward by virtue of the weight of the patient, resilient 60 means for automatically controlling the downward movement so as to align the parts of the body of the patient and resiliently maintain them in such alignment and means for locking the sections in any desired alignment.

4. An operating table of the class described comprising supporting means, sections arranged end to end and pivotally mounted on said means to provide a supporting surface upon which a patient may lie, the adjacent ends of the sections being adapted to move downward by virtue of the weight of the patient, a rod secured to and depending from the under side of each section, and a spring arranged on each rod to automatically control the downward movement of its section and thereby to bring the sections in a position at which the parts of the body of the patient are aligned and in which said parts are resiliently maintained in alignment. 70 75 80

5. An operating table of the class described comprising supporting means, sections arranged end to end and mounted on said means to provide a supporting surface 85 upon which a patient may lie, the adjacent ends of the sections being adapted to move downward by virtue of the weight of the patient, a semi-circular rod secured to and depending from the under side of each section, said rod being concentrically arranged about the pivot of its section, a cross bar arranged under each section and adjacent to said rod and a spring arranged on each rod and adapted to be compressed between said cross bar and its section upon the downward movement of such section. 90 95

6. An operating table of the class described comprising supporting means, sections arranged end to end and mounted on said means to provide a supporting surface upon which a patient may lie, the adjacent ends of the sections being adapted to move downward by virtue of the weight of the patient, and means 100 for controlling the downward movement so as to align the parts of the body of the patient, said means including duplex springs one of which is adapted to be rendered operative or inoperative at the will of the operator. 105

7. An operating table of the class described comprising supporting means, sections arranged end to end and mounted on said means to provide a supporting surface upon which a patient may lie, the adjacent ends of the sections being adapted to move downward by virtue of the weight of the patient, and means for controlling the downward movement so as to align the parts of the body of the patient, said means including duplex 110 springs one of which is normally operative and the other of which is normally inoperative but adapted to be rendered operative at the will of the operator to accommodate a weight over the range of said spring first 115 mentioned. 120 125

In testimony whereof I affix my signature.

GEORGE A. BREWSTER.
